LAMP STAND

Mel Appel, Murray Hill, and Martin Schnur, West Orange, N.J., assignors to N.J. Thermex Company, Inc., Harrison, N.J., a corporation of New Jersey

Filed Nov. 15, 1961, Ser. No. 67,533

Term of patent 14 years

(Cl. D48—24)

FIG. 1 is a top plan view of a lamp stand showing our new design;

FIG. 2 is a front elevational view;

FIG. 3 is a rear elevational view; and

FIG. 4 is a side elevational view looking at the right side of FIG. 2.

The lamp in broken lines in FIG. 4 is for illustrative purposes only.

We claim:

The ornamental design for a lamp stand, substantially as shown and described.
